TELEPHONE SYSTEM.

1,271,133.

Specification of Letters Patent.

Patented July 2, 1918.

Application filed August 1, 1917. Serial No. 183,873.

To all whom it may concern:

Be it known that I, HENRY P. CLAUSEN, a citizen of the United States, residing at Mount Vernon, in the county of Westchester 5 and State of New York, have invented certain new and useful Improvements in Telephone Systems, of which the following is a full, clear, concise, and exact description.

This invention relates to telephone systems involving the use of mechanical switching apparatus for establishing connections between subscribers' lines.

In particular it pertains to means whereby a thorough and efficient supervision of 15 the traffic handled by such a system may be readily had. Where the number of subscribers' lines is sufficiently large to warrant the employment of selector as well as connector switches, it is the general practice to 20 connect the trunk terminals of each access point in a selector level to the corresponding terminals in the same level of other selectors. Likewise the terminals of all the levels are multiplied throughout the group. The number 25 of access points per level of the selector switch is governed largely by the volume of traffic in the particular system involved, but as an arbitrary figure we will assume that, with a proper and adequate distribution of 30 lines, a ten per cent. provision will be sufficient to take care of the maximum number of simultaneous calls. This means that for each level of the selector there will be ten access points, each multiplied to other 35 switches as above observed, and each multiple leading to a connector. There will then be ten connectors per level of the selector switch, each connector having access to 100 subscribers' lines, so that any call coming 40 into this particular group of 100 lines must be extended over that group of trunks which comes from the same level of the selector switches.

It frequently is the case that, due to an 45 inaccurate knowledge of the volume of traffic over each line, or owing to conditions which vary the volume of traffic over a certain group of lines, one or more groups of switches may become congested to such an 50 extent that such group or groups will not be capable of handling the traffic. On the other hand, in all probability other groups will contain less busy lines and the percentage of switches affording them service 55 is greater than is really necessary. This is

not always indicative of an insufficient percentage of trunks and switches when the entire system is considered. All that is often necessary is a proper redistribution of those lines which are occupying trunks an abnormally large portion of the time. 60

It is therefore an object of this invention to provide means at the selector switches so that an attendant will be immediately apprised when a certain group of trunks in 65 the system is becoming overloaded due to the large amount of traffic it is called upon to handle. With this knowledge in mind and by means of certain provisions associated with the connector switches, which also 70 forms a part of this invention, he will be able to isolate the abnormally busy lines down to the particular small group or groups of subscribers' lines. The undesirable condition may thereupon be quickly relieved by merely shifting a portion of the 75 lines to less busy groups.

Systems heretofore proposed for the traffic supervision of trunk groups have been more or less unsatisfactory in that they do 80 not afford the real knowledge desired. It is not new to observe the number of times a group of trunks are all busy simultaneously. But this is not sufficient for, although it is a safe assumption that some calls are lost during the time all trunks are busy, there is always the uncertainty as to whether a sufficient number are lost to warrant a redistribution of the lines served by that particular group of trunks. In accordance with the 85 present invention means are provided whereby an exact record is obtained of the number of calls that fail to secure service over any group of trunks in the system, due to all trunks of such group being busy at the time 90 the call was made.

In the drawing accompanying this specification, and from a study of which the objects and advantageous features of this invention will become readily apparent, there 100 is shown diagrammatically the switches and apparatus used for setting up a connection between two subscribers' lines.

Assume the subscriber whose substation equipment is illustrated schematically at 1 105 wishes to place himself in communication with the subscriber at station 2. Upon the removal of his receiver a circuit is closed in the well known manner to operate a finder or other switch to place its brushes 3, 4 and 110

5 in connection with the terminals 6, 7 and 8 of the calling line. This extends the connection to an idle selector switch, closing a circuit as follows for the selector line relay 9: free pole of battery, left-hand winding of relay 9, back contact and inner lower armature of relay 10, trunk conductor 12, brush 4 and terminal 7, over the loop of substation 1, terminal 6 and brush 3, trunk conductor 11, upper armature and back contact of relay 10, right-hand winding of relay 9 to ground. Relay 9 energizes and attracts its armature, thereby establishing a circuit from ground, armature and front contact of relay 9, winding of slow release relay 13 to battery, and in which circuit said relay becomes energized. The foregoing operations have all occurred in a brief space of time due to the removal of the calling party's receiver, and before any impulses are sent.

The sender dial 14 is now manipulated to impress upon the line a series of impulses corresponding in number to the first digit of the called substation's number. This series comprises the group selecting impulses which, in a system utilizing only first selectors, such as the one chosen to illustrate the present invention, operate the selector to position its brushes in proper relation with the particular trunk group having access through succeeding connectors to the group of say 100 subscribers' lines in which the desired line appears. The brushes 15, 16 and 17 of the selector are elevated into proper relation with said trunk group level by means of a primary stepping magnet P M which is actuated at each retraction of the relay 9 as the impulses are sent out by the sender 14. The circuit for P M leads from ground, armature and back contact of relay 9, conductor 18, contact and lowermost armature of relay 10, conductor 19, inner armature and front contact of relay 13, slow release relay 20, magnet P M to battery and ground. At its outer armature and contact, the slow relay 13 puts a ground on the terminal 8 and all of its multiples at the finder or other preliminary switches. This ground is projected over the conductor 21.

During the primary or group selecting series of impulses the selector brushes 15, 16 and 17 are brought to a point opposite the level of trunk terminals of trunks having access through succeeding connectors to the group of lines of which the desired subscriber's line 2 is one, and which level of trunk terminals is shown as the uppermost in the figure.

At the time the relay 20 was energized, when relay 9 retracted its armature in response to the first impulse, it closed a circuit for the relay 22 from ground, front contact and armature of relay 20, conductor 23, winding of 22 to battery and ground. Relay 22 attracted its armature and thereby locked

up, as soon as the brush shaft had taken its first step and closed the off-normal contacts O N, over a circuit from battery, winding of 22, front contact and armature of 22, conductors 24 and 25, contact and right-hand armature of secondary stepping magnet S M, conductor 26, off-normal springs 27 and 28, conductor 21 to ground at the outer armature and contact of relay 13. The relay 20 being slow to release does not retract its armature at this time, but maintains it in its actuated position to hold a break point in the circuit of magnet S M, as will presently appear, until after the last impulse of the series has been transmitted.

At the termination of said impulse series and when relay 9 holds its armature attracted for a sufficient period of time, relay 20 retracts its armature and closes at its back contact a circuit for S M as follows: free pole of battery, winding of S M, left armature and contact of S M, back contact and armature of relay 20, conductor 23, front contact and armature of relay 22, conductors 24 and 25, contact and right-hand armature of S M, conductor 26, off-normal springs 27 and 28, conductor 21 to ground at the outer armature and contact of relay 13. The secondary stepping magnet S M energizes in this circuit and steps the selector brushes 15, 16 and 17 onto the first set of trunk terminals in the selected level.

Assume, for example, that the trunk represented by the first set of terminals, and that all other trunks preceding the trunk 29, 30, 31, are busy at the time. Thus, when magnet S M gives the selector brushes their first step, and at the same time interrupts its own circuit as well as that of relay 22, a new circuit will be immediately substituted for relay 22 before the same has time to retract its armature. Such circuit is traceable from ground, contact and outer armature of a relay corresponding to relay 32 of the connector shown in the figure, but individual to the particular connector associated with the first trunk in the level, a test conductor corresponding to 31, test brush 17, conductor 24, armature, front contact and winding of relay 22 to battery. Relay 22 therefore holds its armature attracted so that when magnet S M retracts its armatures, said magnet is again energized and advances the brushes onto the next set of trunk terminals, and so on until said brushes finally make contact with the terminals of an idle trunk, which, as assumed in the present instance, is the trunk 29, 30, 31.

Since the connector to which this trunk leads is idle, its associated relay 32 will be deenergized and consequently no circuit will be established for the relay 22. Thereupon, the relay 22 retracts its armature and opens the circuit of S M, bringing the selector brushes to rest on the idle trunk.

A circuit is also closed for cutoff relay 10 from free pole of battery, winding of 10, conductor 33, back contact and armature of relay 22, conductors 24 and 25, contact and armature of S M, conductor 26, off-normal springs 27 and 28, conductor 21, to ground at the outer armature and contact of relay 13. Relay 10 by attracting its armatures extends the trunk conductors 11 and 12 to the brushes 15 and 16, and thence over the trunk 29, 30, to the connector switch shown in the figure.

Immediately that the relay 10 is actuated, a circuit is completed for the line relay 34 of the connector switch, traceable from free pole of battery, right-hand winding of 34, back contact and inner lower armature of reverse current relay 35, trunk conductor 30, brush 16, front contact and inner lower armature of relay 10, trunk conductor 12, brush 4, terminal 7, over the loop of substation 1, terminal 6, brush 3, trunk conductor 11, upper armature and front contact of relay 10, brush 15, trunk conductor 29, upper armature and back contact of relay 35, the left-hand winding of relay 34 to ground.

Relay 34 on attracting its armature closes a circuit for slow release relay 32, from ground, armature and front contact of relay 34, winding of 32 to the free pole of battery.

It is obvious that upon the energization of relay 10 circuit for the selector line relay 9 is interrupted, permitting the same to retract its armature, which in turn opens the circuit of relay 13 and allows the latter to also release its armatures. When the outer armature of relay 13 retracts, ground is removed from the previously traced circuit of relay 10. But since relay 13 is slow to release, a new circuit for relay 10 is completed at the armature of relay 32 before relay 13 has time to deenergize. Such circuit may be followed from ground, contact and outer armature of relay 32, test trunk 31, test wiper 17, conductor 24, armature and back contact of relay 22, conductor 33, winding of relay 10 to battery and ground.

At the outer armature of relay 32, a ground is also placed upon the multiple test terminals of other switches in the group so that no other selector will be able to seize the trunk 29, 30, 31.

The apparatus is now in condition to receive the second or tens series of impulses, and upon the transmission of this series and in response thereto the relay 34 is actuated. At each retraction of the armature of relay 34 a circuit is completed from ground, armature and back contact of relay 34, inner armature and front contact of relay 32, slow release relay 36, primary stepping magnet P' M', contact and side-switch arm 37 in position 1, to battery. Magnet P' M' thus being energized at each impulse, steps the connector brush shaft 38 and its associated

brushes up to the level of contacts containing those of the called line. Relay 36 also energizes in this circuit, and being slow to release retains its armatures while the impulses are being sent.

At its outer armature relay 36 completes a circuit for the private magnet 39, from ground, outer armature and contact 40 of relay 36, conductor 41, magnet 39, to battery and ground. Magnet 39, which controls the movement of the side switch, is thus energized. When, at the cessation of the tens series of impulses the line relay 34 holds its armature up for a considerable period, relay 36 is deenergized and releases its armatures. The previously traced circuit for magnet 39 is thus opened and upon its deenergization the side switch is stepped into position 2.

Before describing the operation of the connector in response to the last or units impulses, whereby it places its brushes upon the terminals of the desired line, it will be well to consider at this point the adaptation of certain features associated with the connector apparatus, and by means of which the aforementioned objects are attained. It was stated hereinbefore that an attendant at the central station after having been informed by means of certain instrumentalities associated with the selector switches (later to be explained) of the abnormally busy condition of any particular group or groups of trunks, could thereupon immediately ascertain the particular small group of, say ten subscribers' lines that are responsible for this condition.

In accordance therewith arrangement is made so that a record may be obtained of every call made into any group of lines represented by a level of terminals at the connector switch. To this end each connector is provided with a separate vertical row of terminals, one terminal for each level of line terminals, and diagrammatically illustrated in the figure as being below the line terminals banks. Each brush shaft, as the shaft 38, is provided with a supplemental brush, as the brush 42, which is arranged to wipe over said vertical row of terminals while the brush shaft is participating in its primary or elevating motion. Each of the terminals of this row may be conveniently multiplied to other and corresponding terminals throughout the group of connector switches. Each of said multiples will then be connected to a registering magnet 43, which, through the agency of a pawl and ratchet operated counting wheel 44, produces a record every time it becomes energized. Obviously, there will be a registering magnet for each level of terminals in the connector group, or in other words, for each small group of lines.

Returning now to the point where the tens impulses had been sent to step the connector

4

shaft 38 and its associated brushes 45, 46, 47, 42 up to the proper level, it will be seen that at the termination of these impulses the relay 36 retracts its armatures during the interval that the connector brushes are at rest and prior to the transmission of the last series of impulses from the calling station. At such time, the supplemental brush 42 will be resting on the particular terminal corresponding to the level opposite which the line wipers are positioned. Therefore, when relay 36 deenergizes a circuit is closed from ground, armature and front contact of relay 34, conductor 48, contact and inner armature of relay 36, conductor 49, contact and side-switch arm 50 in position 1, conductor 51, brush 42, to the registering magnet 43, and thence to battery and ground. The magnet 43 is energized and operates its armature before the private magnet has time to pass switch-arm 50 out of position 1, the circuit of said private magnet 39, as above noted, being also interrupted upon the deenergization of slow release relay 36. Therefore, whenever a call is made to any line whose terminals appear in any level of a group of connector switches, with which level a recording magnet 43 is associated, a record of such call will be made.

30 By this time the subscriber at station 1 is ready to operate his dial for the units or final digit of the called number. As before, the relay 34 vibrates its armature in response to these impulses, and at each retraction thereof the following circuit is closed: ground, armature and back contact of relay 34, inner armature and front contact of relay 32, relay 36, contact and outer left-hand armature of relay 52, secondary magnet $S' M'$, side switch arm 37 in position 2, to battery and ground. In this manner the magnet $S' M'$ steps the brushes 45, 46, 47, over the selected level and brings them to rest on the terminals of the desired line.

45 If at this time the called line is busy a guarding ground will be present on its test terminal. The circuit affording this busy condition will extend from ground, the side-switch arm and its third contact corresponding to 53, of the connector which is occupying the line, over a conductor corresponding to 54, to the multiple test terminal of the busy line, and thence to the test brush 47 of the connector shown in the drawing, conductor 54, side-switch arm 53 in position 2, conductor 55, contact 56, winding of relay 52, conductor 57, contact 40 of relay 36, conductor 41, private magnet 39 to battery and ground.

55 It will be seen that the contact 40, being of a make-before-break character, closes its connection with conductor 57 before breaking engagement with the outer armature of relay 36. Hence, if the called line is busy, a ground will be substituted over the circuit just traced to take the place of the ground previously provided by the outer armature of relay 36, which retracts at the end of the final series of impulses. The private magnet 39 is thus retained in its energized condition 70 to prevent the side switch from advancing into position 3.

At the same time and in the same circuit, the relay 52 energizes and attracts its armatures. At the right-hand armature and 75 make-before-break contact of relay 52 a ground is substituted at the off-normal spring 58 for the ground at the connector test multiple to maintain the magnet 39 energized. The off-normal spring 58 is closed 80 at this time.

At its inner left-hand armature, the relay 52 establishes a circuit from ground, the secondary winding of the busy-back apparatus 59, inner armature and contact of relay 52, conductor 60, contact and side-switch arm 61, in position 2, condenser 62, trunk conductor 30, and thence through the loop of substation 1, back over trunk conductor 29, upper armature and back contact of relay 85 35, through the left-hand winding of relay 34 to ground. Busy-back current flowing in this circuit produces a characteristic sound in the calling subscriber's receiver to inform him that the desired line is busy. 95

He thereupon replaces his receiver, which opens the line circuit including the circuit of the connector line relay 34. Relay 32 is deenergized and releases its armatures.

The following release circuit may now 100 be traced: ground, armature and back contact of relay 34, inner armature and back contact of relay 32, off-normal spring 63, which closed on the first primary step, release magnet $R' M'$ to battery and ground. Release magnet $R' M'$ operates to restore the connector switch to normal position. The retraction of its armatures by relay 32 also severed the previously traced holding circuit for the cut-off relay 10. Relay 10 upon deenergizing closes the following 110 release circuit for the selector switch: ground, armature and back contact of relay 9, conductor 18, contact and lower armature of relay 10, conductor 19, inner armature and 115 back contact of relay 13, off-normal springs 64 and 65, release magnet $R M$, to battery. The selector switch is thereby returned to normal.

If the called line is idle, no ground is 120 present on the test multiples to hold the private magnet 39 energized when relay 36 releases. Private magnet 39 therefore deenergizes and allows the side switch to advance to position 3.

As side-switch arm 37 goes into its third position, a circuit is closed from free pole of battery, side-switch arm 37, conductor 66, right-hand armature and contact of ringing cut-off relay 67, conductor 68, ringing relay 125 130

69, interrupter 70, to ground. The interrupter 70 alternately opens and closes this circuit, and at each closure the relay 69 attracts its armatures to project ringing current over the called line. The ringing circuit is traceable from the ringing source conventionally shown at 71, front contact and upper armature of relay 69, line wiper 45, through the ringer of substation 2, line wiper 46, lower armature and front contact of relay 69, to ground.

Upon the called subscriber removing his receiver a circuit is closed from battery, upper winding of relay 35, upper armature 15 and contact of magnet 39, back contact and lower armature of relay 69, at the time the brush of interrupter 70 rests on an insulating segment, line wiper 46, over the loop of substation 2, line wiper 45, upper armature 20 and back contact of relay 69, lower armature and contact of magnet 39, lower winding of relay 35 to ground. Relay 35, at its lower armature closes a circuit from ground, side-switch arm 53, in position 3, conductors 54 25 and 72, lower armature and contact of relay 35, winding of relay 67 to battery and ground. Relay 67 energizes and at its left armature closes a locking circuit independent of the armature of relay 35, and at its right-hand 30 armature interrupts the previously traced circuit of the ringing relay 69.

With side-switch arms 61 and 73 in their third positions a talking connection is completed between the calling and called substations. Side-switch arm 53 places a guarding ground potential on the test multiples of all connectors in the group, over the conductor 54 and test wiper 47. At the termination 35 of the conversation, the calling subscriber by hanging up his receiver restores the apparatus as hereinbefore described.

From the foregoing description the method of procedure and operation of setting up a connection, in the particular system chosen 45 for illustration, will be clearly understood by those skilled in the art.

A consideration of the means employed by the present invention for ascertaining the load or amount of traffic that any group of 50 selector trunks is handling will now be given. The above description of the extension of a connection between the substations 1 and 2 was, of course, based upon the assumption that at least one selector trunk of the trunk 55 group having access to the group of lines to which substation 2 is individual, was idle at the time the call was made. If at such time, however, all trunks of this group are engaged, the selector switch in its secondary 60 trunk hunting movement will find a busy ground, as before explained, on the test terminal corresponding to each trunk access point throughout the level. The brushes 15, 16, 17 are therefore stepped over the entire level, and upon moving off the last

trunk contacts the test brush 17 steps onto a terminal of an additional vertical row of terminals.

From this auxiliary terminal a conductor 74 leads to a registering magnet 75, similar 70 to the registering magnet 43 above described. A circuit is now traceable from free pole of battery, magnet 75, conductor 74, test brush 17, conductor 25, contact and right-hand armature of S M, conductor 26, off-normal 75 springs 27 and 28, to ground at the outer armature and contact of relay 13. Registering magnet 75 thereby energizes and registers one count on the device 76.

As explained in connection with the registering system associated with the connector switches, each one of these auxiliary terminals will be multiplied level by level to similar and corresponding terminals in other selector switches, and a registering device 80 like the one shown will be connected to each multiple. Hence, every time a selector switch attempts to extend a call over any group of trunks represented by any particular level of terminals, and finds all trunks 85 of such group engaged, the magnet 75 individual to that level is actuated to produce a count upon the device 76. The information afforded in this manner readily shows the exact number of calls that are being lost 90 to any group of trunks in the system, due to the fact that all trunks of such group are busy when the calls are made.

If it is discovered that a certain group 100 of trunks is losing a large number of its calls, this indicates that the particular group of, say 100, subscribers' lines served thereby, contains a relatively large number of lines that are occupying the use of said trunk group as called lines a large portion of the 105 time. Having secured this information, it then remains to determine the exact location of such lines so that they may be properly redistributed. This is accomplished by the registering devices associated with the connector switches, for, as already explained, 110 a record is obtained thereby of every call made into each small group of lines represented by a level of the connector switches. By thus isolating the abnormally busy lines 115 down to the particular small group or groups of lines, it is then an easy matter to remedy the evil by an adequate redistribution.

It is obvious that the registering devices 120 employed at the connector switches need not be permanently associated therewith. In practice a portable group of ten register magnets 43, could be associated with the particular group of connectors that is desired to be observed.

What is claimed is:

1. In a telephone exchange system, subscribers' lines, selector and connector switches for establishing a connection be- 130

5. Between said lines, means associated with the selector switches for recording the number of calls that fail to secure service due to all of the connectors being simultaneously busy, and means associated with said connector switches for recording the number of calls extended to a group of subscribers' lines.
10. 2. In a telephone exchange system, subscribers' lines, selector and connector switches for establishing a connection between said lines, registering devices associated with the selector switches adapted to register the number of calls failing to secure service due to all the connectors apportioned to such calls being busy, and registering means associated with said busy connector switches for recording the number of calls extended to a group of subscribers' lines.
15. 3. In a telephone exchange system, subscribers' lines, selector and connector switches for establishing a connection between said lines, said connectors being arranged in groups, a group of trunks extending from said selectors to each group of connectors, a registering device associated with each group of trunks and operated by the selector switches to register the number of calls lost by any of said groups due to all the connectors apportioned to such group being busy at the time the calls were made, and registering devices adapted to be associated with any such group of busy connectors and operated thereby for registering the number of calls extended to said group.
20. 4. In a telephone exchange system, selector and connector switches, a group of subscribers' lines arranged in sub-groups and terminating in said connector switches, means including said selectors and connectors for connecting a calling line to any line in said group, means operated by the selector switches for detecting the number of unsuccessful calls due to the simultaneous busy condition of all connectors apportioned to said group, and means associated with each of said sub-groups of lines for recording the number of calls to said sub-group.
25. 5. In a telephone system, subscribers' lines, selector switches having terminal banks arranged in levels and brushes coöperating with said banks, groups of connector switches having terminal banks arranged in
55. levels and brushes coöperating with said banks, a group of trunks interconnecting each selector level and a group of connectors, the subscribers' lines terminating in the terminals of said connectors, operating means for moving the selector brushes over the terminals of any level to seize an idle trunk thereof, operating means for moving the brushes of the connector associated with the trunk seized over any level of said connector terminals to connect with a desired line therein, a registering device associated with each selector level and operated each time a selector finds all the connectors of a group busy, and a registering device associated with each level of such a busy connector group for counting the total number of calls made into said level.
60. 6. In a telephone system, telephone lines divided into groups and sub-groups, selective switches for interconnecting said lines, means for detecting the abnormally busy condition of a group of said lines comprising means for counting the number of unsuccessful calls directed through said switches toward said group, and means for counting the number of successful calls directed through said switches toward each 65 sub-group of said group.
65. 7. In a telephone system, telephone lines, selective switches for interconnecting said lines, and means associated with said switches for recording the number of times 70 said selective switches are actuated during the time all available paths leading from said switches are simultaneously busy.
75. 8. In a telephone system, telephone lines, an automatic switch for interconnecting said lines, said switch having brushes and actuating means therefor, groups of trunks appearing in terminals at said switch, an additional set of terminals associated with the switch and arranged to be engaged by one 80 of said brushes each time the switch fails to extend a call into any of said groups due to the simultaneous busy condition of all the trunks in such group, and registering means operated each time said brush engages said 85 additional set of terminals.
90. In witness whereof, I hereunto subscribe my name this 30th day of July A. D., 1917.
- HENRY P. CLAUSEN.
